Primary Examiner — Katrina N Gonzalez

(57) **CLAIM**

The ornamental design for a PET GOGGLES MASK as shown and described.

DESCRIPTION

FIG. 1 is a front, left, top perspective view of a PET GOGGLES MASK showing my new design;
FIG. 2 is a rear, right, bottom perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof;
FIG. 8 is a bottom plan view thereof; and
FIG. 9 is another front, left side, top perspective view thereof, but shown in a usage state.
The broken lines shown in FIGS. 1 through 9 illustrate portions of the Pet Goggles Mask. The broken lines showing the strap feature in FIG. 9 illustrates environmental structure. The broken lines form no part of the claimed design.
